DESIGN FOR A BOTTLE AND CAN OPENING TOOL

William H. Joyce, Hollis, N. Y.

Application December 9, 1944, Serial No. 116,818

Term of patent 14 years

(Cl. D22—2)

To all whom it may concern:

Be it known that I, William H. Joyce, a citizen of the United States, residing at Hollis, county of Queens, and State of New York, have invented a new, original, and ornamental Design for Bottle and Can Opening Tool, of which the following is a specification, reference being had to the accompanying drawing, forming part thereof.

Figure 1 is an elevational view looking at one side of a bottle and can opening tool showing my new design.

Figure 2 is an elevational view looking at a second side of the tool.

Figure 3 is an elevational view looking at a third side of the tool.

Figure 4 is an elevational view looking at a fourth side of the tool.

Figure 5 is a top plan view.

Figure 6 is a bottom plan view.

I claim:

The ornamental design for bottle and can opening tool, as shown.

WILLIAM H. JOYCE.
